(57) **CLAIM**

I claim the ornamental design for a guitar pick, as shown and described.

DESCRIPTION

FIG. 1 is a perspective view of a guitar pick having a finger engaging pocket extending upwardly from the guitar pick; FIG. 2 is a top plan view of the guitar pick of FIG. 1 showing a bottom of the finger engaging pocket; and

FIG. 3 is a cross sectional view of the guitar pick of FIG. 1, taken along the line 3—3 in FIG. 2; and,

FIG. 4 is a perspective view of the guitar pick of FIG. 1 showing the finger engaging pocket.

The portions of the article in broken lines are shown for illustrative purposes only and form no part of the claimed design.

UNITED STATES PATENT AND TRADEMARK OFFICE
CERTIFICATE OF CORRECTION

PATENT NO. : Des. 561,235 S
APPLICATION NO. : 29/225427
DATED : February 5, 2008
INVENTOR(S) : Douglas C. Larsen

Page 1 of 1

It is certified that error appears in the above-identified patent and that said Letters Patent is hereby corrected as shown below:

On the Title page, Item (57)

Please add, preceding the claim section -- The portions of the article in broken lines are shown for illustrative purposes only and form no part of the claimed design -- and delete, after the Description section "The portions or the article in broken lines are shown for illustrative purposes only and form no part of the claimed design."

Signed and Sealed this

Twenty-fourth Day of June, 2008

JON W. DUDAS
Director of the United States Patent and Trademark Office
